UNITED STATES PATENT OFFICE.

CHARLES DAVIS WELDON, OF MICA, WASHINGTON.

TOBACCO-PIPE.

SPECIFICATION forming part of Letters Patent No. 423,197, dated March 11, 1890.

Application filed November 15, 1889. Serial No. 330,433. (No model.)

To all whom it may concern:

Be it known that I, CHARLES DAVIS WELDON, of Mica, in the county of Spokane and State of Washington, have invented a new 5 and improved Tobacco-Pipe, of which the following is a full, clear, and exact description.

Reference is to be had to the accompanying drawings, forming a part of this specification, in which similar letters of reference indicate 10 corresponding parts in all the figures.

Figure 1 is a perspective view of my new tobacco-pipe, the parts thereof being shown separated from each other. Fig. 2 is a longitudinal sectional elevation of the pipe shown 15 in the preferred construction. Fig. 3 is a similar view showing a modification, and Fig. 4 is a side view showing the stem made in three sections.

The invention will first be described in connection with the drawings, and then pointed 20 out in the claim.

A represents the bowl of the pipe, formed with or provided with the stem-section B.

C represents the mouth-piece, connected to 25 the section B by the ferrule D.

In Figs. 1 and 2 the lower part of the section B and bowl are bored to form the small passage a to receive the point of the cleaning device E, while in Figs. 3 and 4 only the lower 30 part of the bowl is so bored. The cleaner E is of metal secured to one side of the ring f,

which fits on the shank of one of the sections of the stem against one end of the ferrule D, as shown clearly in the drawings. The opening through the sections of the stem is contracted at i at the bowl and at i' at the end of the mouth-piece. This prevents the drawing through of nicotine, and when the sections are separated enables the wiper E, with a swab or cloth applied thereto, to be easily 40 inserted to thoroughly clean out the interior of the sections.

The stem may be made up of three or more sections, as indicated in Fig. 3.

By this construction the pipe may be readily cleaned and the cleaner is always at hand, and, applied as described, it in no manner 45 disfigures the appearance of the pipe.

Having thus described my invention, what I claim as new, and desire to secure by Letters 50 Patent, is—

A tobacco-pipe having its stem made in sections and formed with a recess or socket a, in combination with a cleaner provided with a ring f at right angles to its body and fitted to 55 the joint between the sections of the stem, the parts being combined and operating in the manner set forth.

CHARLES DAVIS WELDON.
